UNITED STATES PATENT OFFICE.

WILLIAM T. MACDONALD, OF HAYDEN, ARIZONA.

MEANS FOR CRUSHING AND GRINDING ORE AND ROCK.

Application filed October 30, 1920. Serial No. 420,612.

To all whom it may concern:

Be it known that I, WILLIAM T. MACDONALD, a citizen of the United States, residing at Hayden, in the county of Gila and State of Arizona, have invented a new and useful Means for Crushing and Grinding Ore and Rock, of which the following is a specification.

This invention relates to the crushing or grinding of ore or rock material in tube mills, ball mills, cone mills, and the like, in which ore or rock is subjected to crushing and grinding action within rotating barrels, drums, or other suitable apparatus, containing crushing and grinding bodies in contact with the ore or rock and operating to crush and grind the same in the tumbling, rolling, rubbing and agitating action due to the rotation of said apparatus. The crushing and grinding bodies used for this purpose have generally consisted of so-called "pebbles" of naturally occurring hard rock, or of balls of metal, such as iron. In the operation of mills of this character with balls or pebbles approximately spheroidal in form, the crushing and grinding action of the balls on the material is generally limited to points of contact, resulting in loss of efficiency and capacity in the crushing and grinding and in undue wear on the crushing bodies at such limited points of contact. In some cases, rods of approximately circular cross-section have been used in the place of balls or pebbles and the contact is then extended to a line of contact but is still comparatively limited.

The main object of the present invention is to provide a form of crushing body for use in mills of this character in which the grinding bodies are adapted for tumbling and falling action in the usual manner of ball and pebble mills, and, in addition, as they approach each other in the tumbling, falling and rubbing action in the mill will present approximately plane surfaces to the material being crushed or ground between said bodies whereby a larger surface of contact for crushing or grinding is secured and at the same time increasing the crushing or grinding effect and decreasing the wear on the crushing or grinding bodies, compared to the effective grinding or crushing performed. This advantage is gained with little, if any, sacrifice of the advisable or necessary interstitial space which

should exist between adjacent grinding media in order to permit of the requisite flow of the ore pulp to, between and around such grinding media and through the containing tube mill, ball mill, cone mill, or other suitable appliance.

Another object of the invention is to provide a more effective crushing and grinding action by subjecting the material to be operated upon to a rubbing and sliding action between approximately plane or flat surfaces as well as to the crushing effect due to falling and tumbling action of the crushing bodies.

The accompanying drawings illustrate suitable embodiments of my invention, and referring thereto:

Fig. 1 is a perspective of one form of the crushing or grinding body;

Figs. 2 to 3 are perspectives of modified forms thereof;

Fig. 4 is a partly broken side elevation of a tube mill provided with crushing and grinding bodies constructed according to my invention;

Fig. 5 is a diagram showing the manner in which approaching grinding bodies constructed according to my invention operate in producing a rubbing and shearing action on the material being crushed.

The crushing and grinding bodies used in accordance with my invention may consist of any suitable material but are preferably of metal, for example, cast or wrought iron, or steel, formed in blocks or bodies having any desired number of plane surfaces, such bodies being preferably formed as polyhedrons, the preferable form being that of a cube or six sided polyhedron, as shown at 1 in Figs. 1 and 2, having the plane surfaces 2 mutually nearly perpendicular to one another. The corners or corners and edges of such cube or polyhedral body are purposely formed as curved, or comparatively narrow beveled surfaces, as indicated at 3 and 4, as the article is supplied for sale or use for crushing and grinding purposes. As shown at 7 in Fig. 3, a portion of the crushing or grinding body may be in the form of an approximately spheroidal surface with the plane surfaces 2 formed thereon.

I find it advantageous that the so-called cubes, or other polyhedral bodies, as hereinbefore described, but purposely formed with

curved or comparatively narrow beveled surfaces at all places where otherwise corners and line edges would naturally have existed.

I wish to point out some of the essential benefits to be derived from purposely forming such just mentioned corners or edges as curved or beveled surfaces. When the crushing or grinding media or bodies are thus shaped, it is impossible for them to be so placed but that interstitial spaces will exist between the adjacent crushing media or bodies, and as these interstitial spaces naturally become filled with the ore or rock particles to be crushed, such interstitial material is readily available and is introduced between any two adjacent surfaces of the grinding media and is subjected to the resulting rubbing, crushing and grinding action. Such interstices also permit of a desirable and necessary flow or travel of the ore or rock particles through the interior of the mill, while forcing them to enter between and to come in proper contact with the crushing media. Also, when the crushing and grinding media or bodies are thus purposely shaped a very material saving in grinding media is effected as compared with the use of crushing or grinding media in which the natural corners or edges have not been so replaced. The corners or edges which would otherwise originally be present would constitute natural points of weakness. Such corners or edges when present wear away rapidly with a comparatively small amount of effective work having been performed, and thus reduce materially the total comparative efficiency of such grinding media. The combination of flat surfaces and of rounded corners and edges that are thus provided in the grinding media herein described is highly desirable and both of these features while possessing their own specific advantages cooperate to effect a combined beneficial result, as above pointed out.

I provide the crushing and grinding bodies above described as articles of manufacture for sale and use in tube mills, ball mills, cone mills, and like apparatus in which a rotary tubular or other suitably shaped barrel or member, such, for example, as indicated at 12 in Fig. 4 is mounted to rotate in suitable bearings 13 and 14, and is driven by operating means 15 and provided with means 17 and 18 for supply and discharge of the material to be crushed or ground; the crushing and grinding bodies 1 being placed in said barrel or rotary member in such manner as to be in contact with the material to be operated upon, indicated at 19.

In the rotation of the mill 12 the mass of crushing and grinding bodies 1 and the ore or rock material 19 contained in the mill is turned over and over, being carried up on the ascending side of the tube, barrel, or drum 12, and falling, sliding and rolling

over in well known manner to effect the crushing and grinding of the ore or rock. When the bodies or billets are of substantially cubical form, the rolling and falling or tumbling action takes place with approximately the same velocity and in the same manner as with spherical balls or pebbles. While in some cases a polyhedral crushing and grinding body, as above described, may in the rolling, sliding or falling action come into contact with or approach another such body at the pointed, curved or angular portion of one or the other of the bodies there will be a larger number of cases in which the bodies will approach one another under such conditions as to present toward one another the approximately plane surface constituted by the side of said bodies, as indicated, for example, in Fig. 5, and in addition to the movement of approach there will be more or less lateral or sliding movement of the approaching bodies relative to each other. The result of such an operation is to cause contact of the bodies with each other and with the ore or rock material, indicated at 19, throughout an extended surface, thereby increasing or distributing the crushing and grinding action over a larger portion of the ore and over a larger portion of the surfaces of the crushing and grinding bodies. This has the effect of increasing the crushing or grinding capacity, as a larger amount of ore or material is subjected to the operation than if the crushing and grinding bodies only approached at a single point. It is true that in this distributed crushing and grinding operation the violence or force of the impact or pressure per unit of area is correspondingly diminished but this is generally an advantage rather than otherwise as the effect of the extremely violent impact and pressure due to contact limited approximately to points is beyond what is necessary for crushing and results in comminution of the material, or a portion thereof, to the condition of dust or to a fineness beyond that which is desired.

Furthermore, the distribution of the crushing and grinding action over a larger surface of the crushing and grinding bodies themselves tends to materially reduce the wear and attrition of these bodies, relative to the quantity and effectiveness of the grinding or crushing performed. A distinct advantage to be gained by the use of the flat grinding surfaces of the grinding bodies herein proposed, is the much greater relative evenness of the resulting ground material. For most metallurgical, and perhaps manufacturing purposes, after an ore or rock has been ground or reduced to a certain degree of fineness any additional reduction in size, is not only wasteful of power, but is usually decidedly detrimental

to the obtaining of the best final results. As indicated elsewhere in this discussion, the use of balls or pebbles of essentially spherical form, or at least of bodies bounded by 5 curved surfaces and crushing by point contacts instead of by surface contact, is productive of a relatively unevenly sized product, and the consumption of an excessive amount of power is necessary to insure all material 10 being ground to at least the minimum size or mesh desired. The flat grinding surfaces of the bodies herein proposed, however, largely insure the protection from further grinding or crushing of the ore or rock particles, 15 which have already been reduced sufficiently in size, for the reason that the approach of the flat surfaces is limited by the size of the larger particles of ore or rock present, and such larger ore or rock particles will of 20 necessity be the first to be acted upon by the flat grinding surfaces, as a consequence of which more even grinding or crushing will be effected. Relatively more material will be ground to at least the minimum size or 25 mesh desired and relatively less will be ground finer than desired, while the total contained energy of the moving grinding media will be much more efficiently utilized.

Another advantage in the use of crushing 30 and grinding bodies having approximately plane surfaces, as described, is that opportunity is given for wedging and rubbing actions due to the approach of the bodies obliquely toward one another, so that lateral 35 components of motion are presented tending to effect rubbing and shearing of the particles, it being recognized that crushing by rolling, rubbing, sliding and wedging action is especially efficient and desirable, 40 this being effected in large measure by the operation of the crushing and grinding bodies having approximately plane surfaces, as described, whereas, it can not be effected to any considerable degree by the ordinary 45 rounded pebbles or balls.

It is believed that appreciably better and cheaper grinding and crushing will result from the use of this proposed grinding medium than is the case when employing either 50 balls or rods of circular cross-section. When employing balls for this purpose, speaking broadly, only a one point crushing contact is probable or often possible between any two adjacent balls. When similarly employing rods or circular cross-section, only a line crushing contact is probable or often possible. But when employing the shape of 55 grinding medium herein proposed, anything from a point to a line and then to a surface 60 contact is possible,—with the surface contact probable a very large percentage of the time.

When employing balls as a crushing medium it is probable that most of the grinding effected results from the immense number of point contacts between falling or

moving adjacent balls, and that the particular particle, or small number of particles, of the material so crushed is probably crushed finer than is necessary or often desirable, while a very considerable portion 70 of the energy of the falling or moving balls is consumed in excessive shock and consequent injury and undue wear to the grinding medium itself. In a similar manner the line contact obtained by the use of rods of 75 circular cross-section probably results in an undue proportion of the energy expended being inefficiently, or probably even injuriously, applied. In the case of the grinding medium proposed the tendency toward surface contact between the individual adjacent crushing bodies or media would tend to more efficiently utilize the total contained energy in performing useful crushing or 80 grinding of the material to be ground and 85 would result in a minimum proportion of such energy being consumed in excessive wear of the grinding medium. By the use of grinding media of the form and shape proposed, effective crushing and grinding 90 work results both from each original impact of any two adjacent grinding media and also from the subsequent rubbing action between any two adjacent grinding media surfaces, 95 which through their tendency to come together will grind or crush the intervening particles of the material to be ground.

A grinding medium of this form or shape can be cast or forged as cheap or cheaper than can spherical balls. 100

The power consumption will be less per unit of material crushed to any given size because of the more efficient grinding or crushing, and also because the containing mill can generally be run more slowly, due 105 to the fact that when using the type of grinding medium herein proposed, proportionately less grinding and crushing will result from the force of original impact between adjacent individual crushing media 110 than is now the case with either balls or rods of circular cross-sections and proportionately more grinding and crushing will be effected through rubbing as also through the effective pressure existing at the contact 115 areas of the crushing media which at any given instance constitute the lower portion of the entire crushing media, such pressure resulting from the cumulative weights of the superimposed crushing media. It will, 120 therefore, not be necessary or advisable to lift the crushing media so high, thus resulting in a saving of power.

What I claim is:

1. Means for crushing or grinding ore or 125 rock comprising a rotatably mounted barrel member provided with means for rotating the same, and for admitting and discharging ore or rock material and crushing or grinding bodies contained within said barrel 130

member, and formed substantially as cubes having flat faces, the corners of adjacent bodies constructed to provide clearance spaces therebetween.

5 2. A crushing and grinding mass of bodies each in the form of a cube having flat faces with surfaces constructed to provide clearance spaces between adjacent grinding bodies at the junctions of the flat faces thereof.

3. As an article of manufacture a crushing and grinding body consisting of a metallic mass of bodies each in the form of a cube having flat faces with beveled edges at the junctions of said faces.

In testimony whereof I have hereunto 15 subscribed my name this 14th day of October, 1920.

WILLIAM T. MACDONALD.
